UNITED STATES PATENT OFFICE.

HENRY A. SWENSON, OF TUSTIN, CALIFORNIA.

DOOR CATCH.

Application filed March 18, 1925. Serial No. 16,362.

To all whom it may concern:

Be it known that I, HENRY A. SWENSON, a citizen of the United States, residing at Tustin, in the county of Orange and State 5 of California, have invented new and useful Improvements in Door Catches, of which the following is a specification.

This invention relates to door catches.

It is an object of the invention to provide 10 a door catch which may find utility in cupboards or in any association between a door and a stationary member so that the door may be firmly secured in one position or another and may be moved from that position 15 merely by exerting sufficient pressure upon the door and without manually releasing any parts of the door catch.

The application of the door catch herein 20 illustrated is in connection with a cupboard and a hinged door, but from the following description it will be apparent that this catch might also be useful in retaining the door of a room in an open position against a wall.

25 Other objects and advantages will be made manifest from the following specification of an embodiment of the invention illustrated in the accompanying drawing, in which:

30 Figure 1 is a perspective of a cupboard having the door catch attached.

Figure 2 is a front elevation of the cupboard showing the door closed.

35 Figure 3 is a fragmentary section showing the door catch and is taken on the line 3-3 of Figure 2.

Figure 4 is a perspective of one member of the door catch.

40 Figure 5 is a perspective of a second member of the door catch.

The details of construction and operation are as follows:

45 The cupboard 1 is provided with a hinged door 2 and a horizontal shelf 3, the forward edge of the shelf 3 being set back sufficiently within the cupboard so that the door 2 may close within the side walls 4 and 5 of the cupboard and the inner face of the door 2 abut against the edge of the shelf.

50 A female latch member 6 is secured to the under side of the shelf 3 and comprises a flat seat 7 having screw holes 8 and 9, the seat being flat and adapted to rest against

the bottom of the shelf. The entire female latch member is preferably formed of a 55 single piece of spring metal, the ends of which are turned down to provide side walls 10 and 11. The side walls may be tapered upwardly toward the rear end of the latch member, and at the forward end of the 60 walls they are depressed toward each other to form a yielding restriction 12 near the opening or mouth 13 at right angles to the seat 7. The extreme forward ends of the 65 walls are bent outwardly to provide a guide-way for the male latch member hereinafter described.

The male latch member comprises a roughly diamond headed screw 15 which is adapted to screw into the door 2 in such 70 position that the head 16 may be received between the side walls of the female latch member. The head 16 is preferably formed with a flat top and a flat bottom parallel with the top, the top and bottom extending forward of an annular shoulder 17. Vertical recesses 18 and 19 are cut in the sides of the head and the forward end has a pair of vertical side walls which taper toward a 75 vertical edge 20.

In the use of the invention it will be readily seen that when the male latch member is 80 screwed into the door 2 and the female latch member is secured to the shelf 3 by means of screws 21, when the door is pushed shut 85 as in Figure 2, the head of the male member will pass between the side of the walls of the female member and the recesses 18 and 19 will be yieldably engaged by restrictions of the side walls of the female member, and the resilient nature of the side walls will 90 tend to cause both latch members to firmly co-operate in retaining the door in a closed position. When it is desired to open the door, knob 22 may be grasped and the door 95 pulled outwardly whereupon the restrictions in the female latch member will yield to release the diamond shape head of the male member and the door may be thrown open.

It will be noted that the vertical walls of 100 the female latch member will compensate for shrinkage or sagging of either the shelf 3 or the door 2, and furthermore that the most satisfactory adjustment between the two latch members may be attained by turning the male screw member in or out so that 105

the diamond shaped head projects the proper distance for engagement with the restriction in the female latch member.

Various changes may be made without departing from the spirit of the invention as claimed.

What is claimed is:

1. A door catch having a female latch member formed of sheet metal bent to form an elongated flat seat with spaced side walls extending directly from the base at right angles thereto, the side walls forming a mouth at right angles to the base, the side walls being curved inwardly to form a yielding restriction adjacent the mouth, and a male latch member comprising a diamond-shaped stud with a head portion and a nar-

row restriction between the head and the base of the stud.

2. In a door catch, a female latch member constructed of sheet metal having an elongated flat seat, substantially triangular-shaped side walls bent away therefrom at substantially right angles thereto, the side walls each forming substantially a right angular triangle and having a mouth between the right angular edges extending substantially at right angles to the seat, the side walls having an inward bend to form a yielding restriction adjacent the mouth formed by the right angular edges.

In testimony whereof I have signed my name to this specification.

H. A. SWENSON.
